CLAIM

The ornamental design for an adapter for a video game controller, as shown and described.

DESCRIPTION

FIG. 1 is a perspective view of an adapter for a video game controller, showing the new design

FIG. 2 is a top plan view thereof.

FIG. 3 is a bottom plan view thereof.

FIG. 4 is a right-side elevation view thereof.

FIG. 5 is a left-side elevation view thereof;

FIG. 6 is a front-side elevation view thereof, and in a rotate position.

FIG. 7 is a rear-side elevation view thereof.

FIG. 8 is a perspective view thereof when not installed on a controller.

FIG. 9 is a top plan view of FIG. 8.

FIG. 10 is a bottom plan view of FIG. 8.

FIG. 11 is left-side elevation view of FIG. 8.

FIG. 12 is a right-side elevation view of FIG. 8.

FIG. 13 is a front-side elevation view of FIG. 8, and in a rotate position.

FIG. 14 is a front-side elevation view of FIG. 8.

The broken lines in the drawings depict portions of the adapter for a video game controller that forms no part of the claimed design. The broken line controller, shown in FIGS. 1-7, illustrates the environmental structure and forms no part of the claimed design.
